CLAIM

The ornamental design for a golf club head, as shown and described.

DESCRIPTION

FIG. 1 is a bottom plan view of the golf club head; FIG. 2 is a toe-side elevational view thereof; FIG. 3 is a heel-side elevational view thereof; FIG. 4 is a rear elevational view thereof; and, FIG. 5 is a cross-sectional view thereof taken along line 5-5 in FIG. 4.

The dot-dash chain lines illustrate the boundaries of the claimed design and form no part of the claimed design. The broken lines illustrate environmental subject matter and form no part of the claimed design. The two solid-line crosshatch patterns each represent an area having a different surface texture, surface treatment, color, and/or material from the other.
